ELECTRIC CLOCK

Arthur F. Poole, Ithaca, N. Y.

Application August 11, 1931. Serial No. 556,369

5 Claims. (Cl. 58—29)

My invention is an electric clock and has for one of its objects the provision of an improved impulse mechanism for the pendulum to the end that the impulse required to keep the pendulum in vibration shall be uniform.

Another object of my invention is an improved contact making device including a triode and associated circuits, thereby taking advantage of the relay action of the triode to reduce the current broken at the contact of the clock to a minimum.

A further object of my invention is an impulse device which will give the impulse during a small arc of the pendulum's swing, leaving the pendulum to swing undisturbed during the remainder of its swing. While, with my herein described impulse device, I can give the impulse at any point of the pendulum's swing, I prefer to give it just as the pendulum leaves the zero point of its swing. At that point its kinetic energy is a maximum and a disturbance produces the least effect on its period.

A further object of my invention is the provision of an impulse device which will be simple to make and reliable in its operation. The above and other objects of my invention will be pointed out in the following specification and claims.

Referring now to the drawing, Fig. 1 is a more or less diagrammatic view of a clock embodying my invention and Fig. 2 is a detail of the impulse roller and its mounting on the pendulum.

In Fig. 1, 11 is the framework in which is the suspension spring 12 supporting the pendulum 10 on which is mounted the impulse roller 13, turning on a shaft 14 pivoted in the bridge 15 and the pendulum 10. The pendulum 10 is provided with a bob 16 supported on a regulating nut 17 threaded on the pendulum rod.

A block 19 fastened to the framework supports an impulse spring 18 which is made of a flat spring strip and has a hump 20 therein to engage the roller 13. The end 28 of the spring 18 is bent at a right angle as shown to contact with a button 22 on the end of a lever 23 pivoted at 24 in the framework. The button 22 is preferably made of a metal suitable for electric contacts such as gold or platinum and the end 21 is also provided with a tip of similar metal to prevent oxidation. Banking screws 25 and 26 limit the motion of the lever 23 against the attraction of an electro-magnet 29 on the one hand and a retractile spring 28 on the other. An armature 27 is secured to the lever 23 and is attracted by the magnet 29 when the same is energized in a manner presently to be described.

Neglecting for a moment the circuit connec-

tions to bring the result about, assume that when the end 21 is in contact with the button 22 the magnet 29 is de-energized and when the contact between 21 and 22 is broken the magnet 29 is energized. Then the pendulum swings to the left, the roller 13 encounters the hump 20 which has been held in position by the contact of the parts 21 and 22. When the roller 13 encounters the hump 20, the impulse spring 18 is slightly lifted thus breaking contact between 21 and 22. The magnet 29 is then energized and the lever 23 is drawn to the banking screw 25 against the spring 28. This leaves the spring 18 free to run down the right side of the roller 13 thus giving a push to the pendulum. When the end 21 contacts with the button 22, the magnet 29 is at once de-energized and the retractile spring 28 lifts the lever 23 to the level of the screw 26 carrying the spring 18 with it. The pendulum swing on to the left undisturbed, on its return to the right, the roller 13 again breaks contact between 21 and 22, the magnet 29 is again made, the lever 23 drawn against the screw 25 and the hump 20 runs down the left side of the roller 13 giving another impulse. As soon as the contact is made between 21 and 22, the magnet 29 is again de-energized and the lever 23 returns to its normal position as shown in Fig. 1. This completes the cycle of operation. The pendulum gets an impulse at each swing for the roller 13 picks up the spring 18 at a higher level than said roller leaves it.

Having described the action of the magnet 29, I shall now describe the circuits needed to bring this action about. The system consisting of the lever 23, the retractile spring 28, and the banking screws 25 and 26, is electrically insulated from the spring 18, which with the pendulum is grounded on the framework. To operate the magnet 29, I use a triode 50 containing the usual filament 51, plate 52 and grid 53. An A battery 47 heats the filament 51, a B battery 48 supplies plate current, and a C battery 49 at certain times puts a negative bias on the grid. The circuit will be apparent from the figure, the plate 52 is connected by the conductor 54 to the magnet 29, then by the wire 55 to the magnet 39 (to be described later) then by the wire 56 to the plus side of the B battery 48. The contact 21—22 controls the bias of the grid 53 which is connected by a conductor 57 to the lever 23. The button 22 on this lever at certain times, contacts with the end 21 of the spring 18 which is connected by the conductor 60 with the negative pole of the C battery 49. A grid leak 58 is connected from the grid to the filament by 110

a conductor 59. The bias of the grid is so chosen that when 21 and 22 are in contact the plate current is blocked, consequently at this time the magnets 29 and 39 are de-energized. When the 5 contact 21—22 is broken the plate current flows through the magnets 29 and 39 and they attract their associated armatures 27 and 38.

I consider this circuit using a triode to control the current required for the operation of the 10 magnet 29 of great advantage. To begin, the force of the spring 18 is quite small, since it is desirable to confine the arc of the pendulum to about one degree on either side of zero. This 15 results in a small force between the contact points 21 and 22, therefore any corrosion of said contacts would be undesirable. With the improved circuit herein shown, the grid current is on the order of ten microamperes, an amperage too small to have any deleterious effect on the integrity of 20 the contact points. Further a resistance of half a megohm may be inserted in the grid circuit without effect on the plate current, so the operation of the contacts is not effected by variations of resistance in the contact points.

25 There remains to explain the operation of the magnet 39. This is to operate a step by step jumper to count the swings of the pendulum. To this end I have provided a ratchet wheel 30 to be driven by a pawl 31 and retained from backward rotation by a click 32. The pawl 31 is on a lever 33 which is moved between the stops 34 and 35, pivoted at 36, held to the stop 35 by a spring 37 and having an armature 38 attached thereto which is attracted by the magnet 39 when the 35 same is energized by plate current as previously described. The wheel 30 is on a rotatable shaft 41 and has a pinion 40 attached thereto which drives a third wheel 42 on a shaft 43 and having a pinion 44 which drives the center wheel 45 to 40 which is attached the minute hand 46. Suitable motion work (not shown) serves to drive an hour hand at the proper ratio. Preferably the gear ratio between the wheel 30 and the wheel 45 is 60 to 1, so that a second hand may be attached 45 to the shaft 41.

While I have shown a jumper type of movement to keep track of the beats of the pendulum, evidently the currents made at each beat of the pendulum could be used to keep an independent 50 clock movement in synchronism therewith. A suitable independent clock movement for this purpose is the well known slave clock of Shortt described in Electric Clocks by F. Hope-Jones, published by N. A. G. Press, Old St., London, 55 England. Referring to Fig. 116, page 209, the currents from the pendulum of my herein described clock are led through the magnet M in said figure and will thus synchronize the pendulum D of the slave clock with the pendulum of 60 my clock described herein. In the description of the Shortt clock the synchronizing currents are applied each half minute, however the synchronizer will work perfectly well if the impulses are applied at each beat of the pendulum. These 65 impulses have no effect on the slave pendulum until it gets slow, they then bring it into step with the governing pendulum. This arrangement would have the advantage of not losing the count in the event of a temporary interruption of current. 70 The slave clock will continue to run and move its hands in spite of an occasional interruption of the synchronizing impulses, it is only necessary that during such interruption the slave pendulum does not get out of step a quarter of a period. When 75 the impulses are resumed the slave is soon brought

up to synchronism. Therefore the count will not be lost.

The impulse system consisting of the spring 18 and the wheel 13 should be made as light as consistent with strength. The spring 18 could be replaced by a gravity arm pivoted at 19 without departing from the spirit of my invention.

For the most refined work, it would be desirable to duplicate the roller 13 and the spring 18 at the back of the pendulum. This to give an impulse which would be symmetrical with the plane of the swing of the pendulum. In this event, the back spring 18 would be connected to the front one so both springs would be controlled by the lever 23.

I have shown my invention applied to a pendulum, however, it is also of use when applied to a balance wheel. In this event the impulse wheel 13 would be mounted on and rotate with the balance wheel, being suitably counter poised. When so used, it will give an impulse which is constant in amount and leaves the balance detached through a larger portion of its arc than a chronometer escapement.

The amount which the action of the roller 13 on the hump 20 separates 21 and 22 may be very small owing to the small current between the said contacts. I have found a separation of a few thousandths of an inch to be ample. As soon as the negative bias is taken off the grid by the breaking of contacts 21—22 the magnet 29 at once 100 pulls the lever 23 to its lower position.

The impulse should be so arranged that if for any reason the current is interrupted, of the contact 21—22 fails to function and the lever 23 remains in its attracted position, the roller 13 will pass under the impulse spring 18 on the return of the pendulum. To this end the screw 25 is so adjusted that the angle of impulse extends about 45 degrees as measured from the center of the roller 13. Then, in the event of a failure of any kind, the roller will pass idly under the hump 20.

It will be evident that the impulse given to successive swings of the pendulum is symmetrical. That is to say that the impulse given when the pendulum swings to the right extends from approximately zero to a certain small angle of the pendulum swing. This impulse, on the following swing of the pendulum to the left, is followed by an impulse which also starts at zero and extends to the same angle in the opposite direction. The preceding is slightly modified by the difference in the angle of the impulse spring 18 when giving an impulse to the right or left, however, the difference is imperceptible and may be made as small as desired by increasing the length of said spring.

My herein described impulse mechanism is the electrical analogue of a chronometer escapement, the lifting of the spring 18 corresponds to the unlocking action and the subsequent fall of the hump 20 on the circumference of the wheel 13 to the impulse. The unlocking is, of course, much less work than is required in a chronometer, and the impulse, being the force of a spring falling through a constant distance, is uniform. Further my device will work without oil on the acting parts, due to the lightness of the acting parts themselves and the extremely small forces involved. The absence of oil makes for permanency of rate.

Attention is directed to my co-pending application 544,839 filed June 16, 1931 for improvement in electric clocks in which I am claiming broadly the combination of a pendulum and impulse means therefor controlled by a triode.

Many changes may be made in the precise struc-

ture herein described without departing from the spirit of my invention, since I claim:—

1. In an electric clock the combination of a pendulum, impulse means for said pendulum adapted to contact therewith intermittently, a triode having a plate and a grid, electric circuits for said plate and grid, an electromagnet connected in the plate circuit of said triode and adapted to flex said impulse means and a contact device operated by said pendulum in the grid circuit of said triode.
2. In an electric clock the combination of a pendulum, an impulse arm disposed to be engaged by said pendulum near the middle of its swing and to be detached therefrom at the end of its swing, a triode having a plate and a grid, electric circuits therefor, an electromagnet adapted to flex said arm in the plate circuit of said triode and a pendulum operated contact device in said grid circuit to open and close the same.
3. In an electric clock the combination of a pendulum, an impulse arm for said pendulum to contact therewith intermittently, a triode having a plate and a grid, electric circuits therefor, an electromagnet in the plate circuit of said triode, an armature for said electromagnet arranged to lift said impulse arm and a pendulum operated

contact device on said armature and in said grid circuit.

4. In an electric clock the combination of a pendulum, a spring actuated impulse arm arranged to give an impulse thereto at approximately right angles to the length of said pendulum, an electromagnet, an armature therefor electrically insulated from said arm, a stop for said armature, a spring to hold said armature against said stop, a triode having a plate and a grid, an electric circuit for said plate having said electromagnet therein and a second circuit for said grid having said arm and armature in series therein.

5. In an electric clock the combination of a pendulum, a spring actuated impulse arm arranged to give an impulse thereto at approximately right angles to the length of said pendulum, an electromagnet, an armature therefor electrically insulated from said arm, a stop for said armature, a spring to hold said armature against said stop, a triode having a plate and a grid, an electric circuit for said plate having said electromagnet therein, a second circuit for said grid having said arm and armature in series therein and a projection on said pendulum adapted to separate said arm from said armature as said pendulum passes said arm.
